UNITED STATES PATENT OFFICE.

FRANK C. HOLBERG, JR., OF PHILADELPHIA, PENNSYLVANIA; ELIZABETH HOLBERG EXECUTRIX OF SAID FRANK C. HOLBERG, JR., DECEASED.

INTERLOCKING DEVICE FOR ELEVATORS.

Application filed February 26, 1923. Serial No. 621,198.

To all whom it may concern:

Be it known that I, FRANK C. HOLBERG, Jr., a citizen of the United States, residing at Philadelphia, county of Philadelphia, 5 and State of Pennsylvania, have invented a new and useful Improvement in Interlocking Devices for Elevators, of which the following is a full, clear, and exact description, reference being had to the accompanying drawings, which form a part of this specification.

My invention relates to an improvement in elevator interlocking mechanism.

Heretofore elevators have been equipped 15 with cooperating mechanism on the elevator car and on the shaft at the landings, whereby the landing gate is prevented from opening unless the car be lined with the landing and whereby when the landing gate is opened 20 the car is prevented from being operated, for example, as shown in the United States Patent No. 1,298,948, dated April 1, 1919.

Such mechanism has been found highly 25 efficient and satisfactory, but an objectionable feature is found in that the contact shoe carried by the car and adapted to be acted on by a shoe or cam on the shaft to actuate the car locking mechanism, when a landing gate is opened, is liable to, and frequently does, contact with the shoe or cam 30 on the shaft, as the car passes a landing at which no stop is made, since the car shoe is carried in forward position and very little clearance from the cam can be allowed.

Contact of the car shoe with the shoe or cam on the shaft, as the car passes a landing, results in unpleasant noise.

My invention has for its object the provision of means, in combination with the 40 interlocking mechanism, for withdrawing the shoe carried by the car when the car is started to insure clearance between it and the shoes or cams at the landings until the car is stopped, when the shoe will be advanced to its forward position for actuation by the shaft shoe on opening of the landing gate.

Having now indicated in a general way 50 the nature, purpose and advantage of my invention, I will proceed to describe a preferred embodiment thereof with reference to the accompanying drawings, in which—

Fig. 1 is a partial face view of an elevator shaft landing gate and of that portion of

the interlocking mechanism coacting therewith.

Fig. 2 is a horizontal section showing the coacting parts of the interlocking mechanism in plan.

Fig. 3 is an elevation, partly in section, 60 of car shoe and actuating cam on the shaft.

Fig. 4 is a section through a portion of an elevator car showing in elevation mechanism for locking the controller of an electric elevator.

Fig. 5 is an enlarged view showing in detail construction of the controller lock shown in Fig. 4.

Fig. 6 is a section through part of an elevator car and shaft, showing mechanism 70 for locking the controller of a hydraulic elevator.

Fig. 7 is an enlarged view showing detail construction of the controller lock shown in Fig. 6.

Referring to Figures 1-5: Inside the elevator shaft, at each landing *x*, is secured a plate *a* which carries the locking mechanism for the landing gate *y*. *z* represents the floor of an elevator car shown as on a level 80 with a landing. A bar *b* extends downward from the gate over the face of plate *a*, the end of the bar being adapted to engage in a notch in a locking disc *c*, when the gate is closed or only slightly open. The position 85 of bar *b* and disc *c*, when the gate is fully closed, is shown in Fig. 1.

A lug *d* is positioned on the disc *c* and the disc *c* is pressed outwardly from behind by a spring, not shown. The lug *d* is adapted, if it be attempted to open the gate when the car is not at the landing, to contact with the end of an angle piece *e* secured to plate *a* and stop the disc *c* before the bar *b* can be withdrawn from the disc, thus preventing the gate from being opened.

Disc *c* carries a cam surface *f* adapted to underride the free end of a plate *h*, hinged on a vertical pivot to plate *a*. A ridge *i* is formed on the front of plate *h* adjacent 100 its free end.

If now the plate *h* be prevented from swinging on its pivot until lug *d* has passed the end of angle piece *e* and it be attempted to open the door, plate *h* will, as disc *c* turns, press the disc back against the action of its spring and causes lug *d* to pass behind angle piece *e* and continue to turn until

another lug d' on disc c contacts with a stop g on plate a by which time disc c will have been turned to a position at which rod b may freely slide out of its slot and the gate 5 is free to open. In the movement of disc c due to the action of cam f , the free end of plate h is swung outwardly, after lug d has cleared the end of angle plate e .

In order to prevent plate h from swinging until lug d has cleared the end of piece e , permitting the gate to be opened, when the car is level with the landing, and in order to effect a locking of the car controller when the gate is opened, certain 10 mechanism is carried by the car.

Beneath the car, and extending in a direction parallel to the edge of the landing floor, is secured an angle frame j to which is secured a bracket to which is hinged an 20 arm h having a vertically extending shoe l formed on its end.

The shoe l is secured to a pin m which extends into a sleeve n , to which it is connected by means of a slot and pin connection o and from which it is pressed, outwardly by a spring p . Sleeve n extends through frame j and is pivotally connected to one end of a lever q , fulcrumed in a bracket r , and the opposite end of which is 30 acted upon by a spring s .

A shaft t is supported beneath the car and provided at each end with a crank u, u' . The crank u is connected to sleeve n by means of a link v , while crank u' is connected to a bar w , which extends up through the floor of the car and is connected to a centrally pivoted plate 2 in the controller easing 3 by means of a slot 4 and pin 5 . The plate 2 carries the car controller handle 6 35 and is rotated on its pivot when the controller handle is moved forward or backward. A keeper 7 is secured to the plate 2 and is adapted to receive the end of bar w to effect a locking of the controller in "off" 40 position.

Assuming now that the car is stationary on a level with a landing: the shoe l lies opposite to the ridge i on the face of plate h and substantially in contact therewith. 50 During the preliminary movements of disc c in opening the landing gate, the plate h will be prevented from swinging by shoe l , which is held in forward position by the action of spring p . After lug d clears the end of angle piece e , the cam surface f acts to swing plate h outwardly, which causes shoe l to be moved back, effecting a backward movement of sleeve n and a rotation of shaft t . When shaft t turns, bar w is 55 raised, and since the controller is in neutral position, the end of the bar enters keeper 7 and prevents movement of the controller handle until the landing gate is again closed and disc c rotated back to its gate locking position. When disc c reaches its gate lock- 60

ing position, shoe l and sleeve n are free to move forward under the influence of spring s and shaft t turns back, withdrawing rod w from keeper 7 , thus freeing the controller. 70

When the car is started, the controller handle is moved back or forward and plate 2 is rotated. As plate 2 rotates, pin 5 rides up in slot 4 , until it reaches the top of the slot when it acts to lift bar w and through crank u' rotates shaft t in a direction to effect a retraction of shoe l through crank u , link v , sleeve n and pin r . Thus, when the car is in motion, the shoe l is retracted and will clear the plate h when the 80 car passes the landings. It will now be obvious that in stopping the car at a landing in bringing the controller handle to neutral, plate 2 is turned and bar w lowered, permitting advance of shoe l to operative position and positioning bar w and keeper 7 for locking the controller when the gate is opened. 85

Referring now to Figures 6 and 7 in which I have illustrated an application of 90 my invention to interlocking mechanism adapted to hydraulic elevators: the mechanism on the shaft and car shown in Figs. 6 and 7 is the same as that in Figures 1-5 except for the controller lock. I have given 95 similar mechanism similar letters and it will not be herein redescribed.

The sleeve n is connected by means of a link 8 to one arm of a bell crank lever 9 , the other arm of which is pivotally connected to a bar 10 adapted to enter a slot 11 in a plate 16 secured to the car. The bar 10 is guided and slidably secured to the control lever 12 by means of a guide 17 . The pivot pin 14 forming connection between bar 10 and bell crank 9 passes through a U-shaped slot 15 in a head formed on the end of bar 10 . 100 105

Assuming now the car to be stopped opposite a landing: as shoe l is pressed back, bell crank 9 is turned and bar 10 raised to enter slot 11 and lock the control lever. When the car is started, control shaft 13 is rotated causing plate 16 to turn and pin 14 rides up in the U-shaped slot 15 , causing bell crank 9 to turn and effect a retraction of shoe l . When the car is again stopped by bringing the control lever 1 to neutral, shoe l is advanced and the control lever is locked when shoe l is pushed back as a result of opening the landing gate. 110 115 120

Having now fully described my invention, what I claim and desire to protect by Letters Patent is:

1. Elevator interlocking mechanism comprising, in combination with an elevator shaft, including a landing and a gate therefor, and a car, a car controller, a shoe on the shaft, a shoe on the car adapted, when the car is stopped opposite a landing, to be ac- 125 130

tuated by the shaft shoe on the opening of the landing gate to effect a locking of the car controller in neutral position, and means adapted, when the controller is moved out 5 of neutral position to start the car, to effect a withdrawal of the car shoe out of position for actuation by the shaft shoe and when the controller is again moved to neutral position to advance the car shoe into position for 10 actuation by the shaft shoe.

2. Elevator interlocking mechanism comprising, in combination with an elevator shaft, including a landing and a gate therefor, and a car, a car controller, a shoe on 15 the shaft, a shoe on the car adapted to be retracted by the shaft shoe on opening of the shaft gate when the car is on a level with a landing, a locking bar, means forming a connection between said car shoe and said 20 locking bar whereby retraction of said car shoe will actuate said locking bar to lock said controller when in neutral position and whereby on movement of said controller out of neutral position a retraction of said car 25 shoe will be effected independently of said shaft shoe.

3. Elevator interlocking mechanism comprising, in combination with an elevator shaft, including a landing and a gate therefor, and a car, a shoe carried by the shaft by and adapted to be advanced on the opening of the landing gate, a shoe carried by the car and adapted to be retracted by the shaft shoe when the car is opposite a landing, a controller on the car, a locking bar, a keeper on the controller adapted to receive an end of the locking bar, when the controller is in neutral position, to lock the controller, means forming a connection between 30 said car shoe and said locking bar whereby, when said car shoe is retracted by said shaft shoe, said locking bar will be actuated to lock said controller, and means forming a connection between said controller and said locking bar whereby when said controller is 35 moved to running position said car shoe will be retracted independently of said shaft shoe.

4. Elevator interlocking mechanism comprising, in combination with an elevator shaft, including a landing and a gate there-

for, and a car, a shoe carried by the shaft adjacent the landing and adapted to be advanced on the opening of the gate, a shoe carried by the car and adapted to contact 55 with and be retracted by the shaft shoe when the car is stopped opposite to a landing, a car controller, a disc secured to said controller, a keeper on said disc, a locking bar adapted to enter said keeper, means affording a connection between one end of 60 said locking bar and said car shoe, and a slot and pin connection between the other end of said bar and said disc whereby when 65 said controller is in neutral position retraction of said car shoe by said shaft shoe will cause said locking bar to enter said keeper and lock said controller, and whereby when 70 said controller is moved out of neutral position said car shoe will be retracted independently of said shaft shoe.

5. Elevator interlocking mechanism comprising, in combination with an elevator shaft, including a landing and a gate therefor, and a car, a shoe carried by the shaft 75 and adapted to be advanced on the opening of the landing gate, a slideable sleeve mounted on the car, a plunger extending within the sleeve and connected thereto by a slot and pin connection, a car shoe secured to the 80 plunger and adapted to align with said shaft shoe when the car is opposite a landing, a car controller rotatable about an axis, a keeper carried by the controller and adapted to receive an end of the locking bar when 85 the controller is in neutral position, means affording a connection between said sleeve and said locking bar adapted, when said car shoe and said shaft shoe are aligned to move said locking bar into said keeper 90 on the opening of a landing gate, to lock said controller in neutral position, and a slot and pin connection between said locking bar and said controller adapted on movement 95 of said controller to effect a starting of the car to effect a retraction of said car shoe independently of the shaft shoe.

In testimony of which invention, I have hereunto set my hand, at Philadelphia, Pa., on this 20th day of February, 1923.

FRANK C. HOLBERG, JR.
